Patented Feb. 20, 1973

226,354

PEDESTAL FIREPLACE

Raynold A. Eld, 302 E. 39th St., Boise, Idaho 83703

Filed Mar. 8, 1971, Ser. No. 122,296

Term of patent 14 years

Int. Cl. D23—03

U.S. Cl. D23—97

FIG. 1

Des 226,354

PAGE 2

FIG. 2

FIG. 3

FIG. 1 is a front perspective view of a pedestal fireplace showing my new design.

FIG. 2 is a rear perspective view thereof.

FIG. 3 is a rear perspective view thereof with a portion of the base broken away to show the grate assembly.

I claim:

The ornamental design for a pedestal fireplace, substantially as shown and described.
